Henry T. Smith - Inventor
By his Atty, S. F. Pease -

UNITED STATES PATENT OFFICE.

HENRY T. SMITH, OF WASHINGTON, DISTRICT OF COLUMBIA.

IMPROVEMENT IN BED-BOTTOMS.

Specification forming part of Letters Patent No. 127,278, dated May 28, 1872.

To all whom it may concern:

Be it known that I, HENRY T. SMITH, of the city of Washington, District of Columbia, have invented new and useful Improvements in Bed-Bottoms; and I do hereby declare the following to be an exact description thereof, reference being had to the accompanying drawing and to the letters of reference marked thereon making a part of this specification, in which—

Figure 1 represents a top view of the bedstead with the improved bottom. Fig. 2 represents one end of the bedstead with the upright thumb-screw plates for adjusting or tightening the wire bottom. Fig. 3 are the wires with the flat end plates, the plate being also shown at Fig. 4.

The nature of my improvement and invention consists in riveting two ends of a wire to a plate, so as to form a double wire with square instead of round ends, the wires resting in straight grooves in the cross-pieces at the head and foot of the bedstead, and being adjusted or tightened by screws at the head-rail of the bedstead. The object is to easily or

quickly repair the bed-bottom in case one of the wires should be broken.

A represents the bedstead; B B, the cross-pieces of the bed-bottom, with straight grooves C cut in for the wires D D to rest in. E E are small metallic plates, to which the ends of wires D D are riveted. The plates E rest against flat plates F that are fastened to the outer sides of the cross-pieces or straining-bars B B. G G are longitudinal stretchers to support the bed-bottom. H H are metallic clips, by which the straining-bars B can be adjusted by screws or plates H with thumb-screws J J.

What I claim as my invention, and desire to secure by Letters Patent, is—

The double wire with square ends, formed by riveting the ends of wires D D to plates E E, as shown at Fig. 3, as herein described, and for the purposes set forth.

HENRY T. SMITH.
